ROTARY INKING MECHANISM AND
PROCESS

Auburn Taylor, Charleston, W. Va., and Emory W. Worthington, Chicago, Ill., assignors to The Goss Printing Press Company, Chicago, Ill., a corporation of Illinois

Application April 21, 1942, Serial No. 439,828

23 Claims. (Cl. 101—350)

The present invention relates to printing presses and more particularly to inking mechanism and processes for rotary printing presses.

Objects and advantages of the invention will be set forth in part hereinafter and in part will be obvious herefrom, or may be learned by practice with the invention, the same being realized and attained by means of the instrumentalities, processes, steps and combinations pointed out in the appended claims.

The invention consists in the novel parts, constructions, arrangements, processes, steps, combinations and improvements herein shown and described.

The accompanying drawing, referred to herein and constituting a part hereof, illustrates one embodiment of the present invention and one form of apparatus for carrying out the process of the invention, and together with the description, serves to explain the principles of the invention.

Of the drawing:

Fig. 1 is a diagrammatic side view of a rotary web perfecting printing press showing the printing couples, inking mechanism and fluid spray mechanism for the inking mechanism;

Fig. 2 is a plan view of certain portions of the inking mechanism shown in Fig. 1; and

Fig. 3 is a diagrammatic view of the fluid spray mechanism for the printing press inking mechanism and control means therefor.

The present invention has for its object the provision of new and novel inking mechanism for rotary printing presses whereby proper substances may be applied to various of the inking members carrying the printing ink for the press, at desired times and for predetermined and desired intervals. A further object of the invention is the provision of means with the inking mechanism for a rotary printing press for applying a finely divided fluid spray to various of the ink rollers and ink drum and to the printing ink on those members in order to properly condition both the ink and the inking members for maximum printing efficiency. The invention further provides a method and means particularly applicable to the use of water base inks in rotary printing presses for the prevention of caking or solidifying of the ink in the inking mechanism and the proper conditioning of the inking mechanism during printing. Still another object is the provision of means with the printing press inking mechanism for applying fluid sprays to the printing ink and the inking

mechanism for definite and desired periods of time and at predetermined intervals.

In accordance with a preferred and illustrative embodiment of the invention illustratively shown in the accompanying drawing there is provided in a rotary printing press a pair of printing couples through which a web of paper is led for printing on both sides of the web. Means are provided for applying printing ink to the printing plates on the form cylinder of each printing couple, and these means comprise an ink fountain with a fountain roller positioned in the ink supply, an ink drum of relatively large diameter, and various transfer rollers for conveying the ink from the fountain rollers to the ink drum and from the ink drum to the form cylinder of the printing couple.

A plurality of vibrating rollers are grouped about the ink drum and have axial reciprocating movement, each out of phase with the other, while the printing press is in operation to distribute the ink from the ink fountain in a uniform enveloping film upon the ink drum before it is transferred to the printing plates. A number of spray nozzles or atomizers are provided on the printing press directed toward the vibrating rollers of the inking mechanism, and these nozzles are connected by suitable fluid pipes to a reservoir containing a fluid and to a compressed air source in order to force the fluid into the nozzles and out in a very finely divided or atomized spray upon the vibrating rollers and portions of the ink drum.

Control means are provided for the fluid spray mechanism which automatically begins the fluid spray and continues it for a variably predetermined interval of time after which the spray is automatically terminated, or the printing press operator may at any time by push button control turn on the fluid spray for as long as is desirable, at a time when the spray is not automatically in operation. According to the illustrative embodiment of the invention herein shown, the control means comprise a solenoid operated fluid valve positioned in the compressed air supply pipe to the atomizing nozzles, and the solenoid is actuated by a relay switch to open the valve. This relay is automatically energized for closing from a spring switch on the main operating control switch of the printing press, so that the spring switch is momentarily closed as the main operating control switch is being advanced from stop or slow to operating speed, and again when the main operating control

switch is being retarded from operating speed to slow or stop. A time delay switch or quick-make-slow-break relay is placed in the circuit of the spring switch and the solenoid actuating relay, so that the compressed air valve may be opened for a period of several seconds or more although the spring switch is only momentarily closed. The spring switch may be positioned at any point along the travel of the main operating control switch depending upon the point relative to the operating speed of the printing press at which it is desired to automatically open the compressed air valve. In the present embodiment of the invention the spring switch is positioned at such a point that it is closed by the main operating control switch when the press is at a very low or inching speed. A push button switch is provided in parallel with the spring switch so that the fluid spray may be actuated by the printing press operator at desired times when the main operating control switch is not in such position as to close the spring switch.

Any fluid may be used in connection with the fluid spray mechanism of the present invention which is desirable and advantageous in improving the operation of the inking mechanism and the printing process. In accordance with the novel and improved process of the present invention, however, it has been found desirable to use as a fluid spray a slowly evaporating or substantially non-volatile liquid miscible with the base of the particular ink being used, in order to prevent drying and caking of the ink when the press is operated at a very slow or inching speed or is brought to a stop, and to lubricate the inking rollers and prevent drying or caking while the press is at speed operation. Where water base inks are being used in the printing operation the mechanism and process of the present invention will be found to be particularly useful, for the essential components of a water base ink are a high percentage of finely divided or colloidal carbon in a water base or vehicle, and with the normal evaporation of the latter the desired proportions of the ink are destroyed and caking of the carbon on the inking mechanism results, both while the press is in operation and particularly when the press is at stop or inching speed. In order to overcome this difficulty and the resulting defective printing and costly delays a hygroscopic spray miscible with the water base of the ink is used in the spraying system.

Example of such sprays are glycerine or diethylene glycol in water solution, which are applied for desired time periods to the various rollers of the inking mechanism by the spraying means of the present invention when the speed of the press is being advanced from stop to operating speed and again when the press is being slowed from operating speed to inching speed or stop, or the spray may be applied at other times as desired by the pressman. A simple water spray from the spraying system has also been found to be very useful in preventing caking of the water base ink and in maintaining the proper composition of the ink.

When the printing operation of the press involves the use of printing inks having volatile petroleum oil bases the spray used may be of kerosene or the like for overcoming the difficulties already mentioned in the use of water base inks.

It will be understood that the foregoing general description and the following detailed de-

scription as well are exemplary and explanatory of the invention but are not restrictive thereof.

Referring now to the embodiment of the present invention illustratively shown in the accompanying drawing a rotary printing press, as shown in Fig. 1, comprises a pair of printing couples each having an impression cylinder 10 and a plate cylinder 11 through which a web of paper W is led in the direction of the indicating arrows by means of idler rollers 12, 13, 14, 15 for printing on both sides of the web. Each printing couple is provided with an inking mechanism, and as illustratively shown these comprise an ink fountain 17 in which the fountain roller 18 is rotatably mounted. The printing ink is conveyed from the ink fountain by means of a pick-up roller 19 and a transfer roller 20 to the ink drum 21 of relatively great diameter, on the outer cylindrical surface of which the ink is distributed in a thin uniform enveloping film by means of vibrating rollers 22, 23, 24 which have an axially oscillating motion, each out of phase with the others. The ink is transferred from the surface of the ink drum 21 to the printing plates on plate cylinder 11 by means of form ink rollers 26, 27, and the impression is thereafter taken on the web W.

The spraying means for the inking mechanism comprises a plurality of spraying or atomizing nozzles 30 which are spaced apart along a length of communicating air pipe 31 and held in position upon the printing press frame or otherwise as may be convenient to lie along the length of the vibrating rollers 22, 23, 24. The communicating air pipe 31 is connected to any suitable source of compressed air through an intake pipe 32, and a manual cut-off valve 33 and air pressure indicating gauge 34 are positioned along the air line. As compressed air arrives from the source along pipe 32, it is received in a relatively large air-tight tank 35 before passing along to the spray nozzles and other parts of the mechanism in order to remove surges in the air and to maintain a steady pressure on the system.

A reservoir 37 is provided to hold the liquid which is to be sprayed upon the inking mechanism, and the compressed air source communicates with the top of the reservoir through pipe 38, in which are placed an adjustable stricture valve 39 and a pressure gauge 40 so that the air pressure on the top of the liquid in the reservoir may be regulated as may be required.

A fluid pipe 41 extends into the bottom of reservoir 37 and thence parallel with the length of air pipe 31. A plurality of needle valves 42 are positioned along the length of the fluid pipe 41 and each lies adjacent one of the spray nozzles 30 and is connected thereto by a flexible fluid conducting hose 43.

The liquid in reservoir 37 is thus forced by air pressure through pipe 41, needle valves 42 and into spray nozzles 30 where it is finely divided or atomized by compressed air entering through pipe 31, and the spray is directed upon the vibrator rollers 22, 23, 24 and portions of the ink drum 21. A shut-off valve 45 is positioned in the air pipe 31 between the compressed air source and the spray nozzles 30, and the opening and closing of the valve is remotely operated by a solenoid shown diagrammatically at numeral 46. This solenoid is actuated from a spring switch 47 which is closed as the main control switch 48 is advanced from a stop to an inching speed position and opened when the main control switch is

further advanced, the main control switch arm 49 engaging a detent 50 on the spring switch at a point where the printing press is at very slow or inching speed.

When spring switch 47 is closed a circuit is completed from the main electric power lines 52, 53 through the lead lines 54, 55, and this circuit includes a time delay switch or quick-make-slow-break relay, which is indicated generally with numeral 56. The time delay switch may be of any suitable and conventional construction and preferably is of a type in which variable delay means are incorporated, and many such switches are on the commercial market at the present time.

The time delay switch, when actuated, closes by means of its arm 60 a circuit from the mains 52, 53 through lead lines 61, 62 and including a relay 63 in the circuit. The relay 63, in turn, by its arm 66 closes a circuit through leads 67, 68 from the mains 52, 53 to the solenoid 46, and the shut-off valve 45 is then opened and spraying continues until time delay switch 56 releases and the circuit to the solenoid is broken. A push button switch 70 is connected in parallel with spring switch 47 enabling the pressman to actuate the fluid spraying system at times when the spring switch 47 is open.

With the spraying system of the present invention the application of a hygroscopic or water spray to a water-base ink may be had at any time when it is required to lubricate and protect the vibrating rollers and ink drum and to prevent the ink from caking on the inking mechanism, and the spray is automatically applied when the press is operating at a very low or inching speed. When printing inks having a volatile petroleum oil base are used in the press kerosene or a similar agent may be used in the spray system to prevent drying out of the ink and consequent undesired caking or tackiness of the ink.

The invention in its broader aspects is not limited to the specific mechanisms, processes and steps shown and described but departures may be made therefrom within the scope of the accompanying claims without departing from the principles of the invention and without sacrificing its chief advantages.

What we claim is:

1. In a rotary printing press having inking mechanism, the combination of means for applying a finely divided liquid spray to the inking mechanism, said means being normally unactuated, means for automatically actuating said first mentioned means to apply said spray when the printing press is operating at a predetermined speed, and means for continuing the actuation of said first mentioned means for a predetermined period of time after the printing press is operating at a different speed.

2. In a rotary printing press having inking means including a plurality of inking rollers, the combination of spray means for applying a finely divided liquid spray to the inking rollers, valve means for permitting and prohibiting operation of the spray means, said valve means being normally closed, means for automatically opening the valve means when the printing press is operating at a predetermined speed, and means automatically maintaining open said valve means for a predetermined period of time after the printing press commences operation at a different speed.

3. In a rotary printing press having inking means including inking rollers, the combination of spray means for applying a finely divided liq-

uid spray to the inking rollers, valve means having opened and closed positions for permitting and prohibiting respectively the operation of the spray means, said valve means being maintained normally in closed position, and means for automatically opening the valve means for a predetermined period of time as the speed of the printing press is brought from high speed to a stop.

4. In a rotary printing press having inking means including inking rollers, the combination of spray means for applying a finely divided liquid spray to the inking rollers, valve means having opened and closed positions for permitting and prohibiting respectively the operation of the spray means, said valve means being maintained normally in closed position, and means for automatically opening the valve means for a predetermined period of time as the speed of the printing press is brought from stop to high speed.

5. A rotary printing press comprising, in combination, an impression cylinder and a plate cylinder for printing on an interposed continuous web of paper, inking means for the plate cylinder including an ink drum and vibrator rollers in peripheral contact therewith, and automatic liquid spray means for the application of a liquid spray to the ink drum and vibrator rollers, said means comprising a liquid spray nozzle adjacent the vibrator rollers, a liquid reservoir, a liquid conveying connection between the spray nozzle and liquid reservoir, a compressed air source, an air conveying connection between the air source and the spray nozzle, a valve in the air conveying connection, a solenoid to open the valve when electrically actuated and means for electrically actuating the solenoid for a predetermined period of time when the printing press is operating at a certain speed.

6. A rotary printing press comprising, in combination, an impression cylinder and a plate cylinder for printing on an interposed continuous web of paper, inking means for the plate cylinder including an ink drum and vibrator rollers in peripheral contact therewith, means for applying a finely divided liquid spray to the vibrator rollers and ink drum including a spray nozzle adjacent the vibrator rollers connected to a liquid source and a compressed air source and a valve between the compressed air source and the nozzle, a solenoid operatively connected to the valve to open the valve when electrically actuated, and means for electrically actuating the solenoid for predetermined periods of time comprising a circuit between an electric power source and the solenoid and including a time delay switch, and a circuit between the electric power source and the time delay switch and including a push button switch.

7. In a fluid spray system for applying a liquid spray to inking rollers of a printing press, in combination, a spray nozzle adjacent the inking rollers, compressed air and liquid supply sources connected to the spray nozzle to supply compressed air and fluid to the spray nozzle, a control valve between the compressed air source and the spray nozzle openable to admit compressed air to the nozzle for forming a finely divided liquid spray, means for automatically opening the valve when the printing press is operating at a given speed, and means for maintaining the valve open for a minimum predetermined period of time.

8. In a fluid spray system for applying a liquid spray to inking rollers of a printing press, in combination, a spray nozzle adjacent the ink-

ing rollers, compressed air and liquid supply sources connected to the spray nozzle to supply compressed air and fluid to the spray nozzle, a control valve between the compressed air source and the spray nozzle openable to admit compressed air to the nozzle for forming a finely divided liquid spray, means under the control of the printing press operator for opening the valve, and automatic means for maintaining the valve open for a minimum predetermined period of time.

9. In a fluid spray system for applying a liquid spray to inking rollers of a printing press, in combination, a spray nozzle adjacent the inking rollers, compressed air and liquid supply sources connected to the spray nozzle to supply compressed air and fluid to the spray nozzle, a control valve between the compressed air source and the spray nozzle openable to admit compressed air to the nozzle for forming a finely divided liquid spray, means under the control of the printing press operator for opening the valve at any desired time, means for automatically opening the valve when the printing press is operating at a given speed, and means for maintaining the valve open for a minimum predetermined period of time after it is opened by the above mentioned opening means.

10. In a fluid spray system for applying a liquid spray to inking rollers of a printing press, in combination, a spray nozzle adjacent the inking rollers, compressed air and liquid supply sources connected to the spray nozzle to supply compressed air and fluid to the spray nozzle, a control valve between the compressed air source and the spray nozzle openable to admit compressed air to the nozzle for forming a finely divided liquid spray, and means for opening the valve for a minimum predetermined period of time, said means comprising a solenoid operatively connected to the valve to open the valve when the solenoid is electrically actuated, an electric circuit between the solenoid and electric power lines including a time delay switch, and an electric circuit between the time delay switch and electric power lines and including a make and break switch.

11. In a fluid spray system for applying a liquid spray to inking rollers of a printing press, in combination, a spray nozzle adjacent the inking rollers, compressed air and liquid supply sources connected to the spray nozzle to supply compressed air and fluid to the spray nozzle, a control valve between the compressed air source and the spray nozzle openable to admit compressed air to the nozzle for forming a finely divided liquid spray, and means for automatically opening the valve for a minimum predetermined period of time when the printing press is operating at a predetermined speed, said means comprising a solenoid operatively connected to the valve to open the valve when electrically actuated, an electric circuit between the solenoid and electric power lines including a time delay switch, an electric circuit between the time delay switch and electric power lines and including a make and break switch, and means for closing the make and break switch when the printing press is operating at a predetermined speed.

12. The process of treating printing ink on the inking mechanism of a printing press consisting of the application of a finely divided liquid spray of slowly evaporating liquid miscible with the printing ink base upon the printing ink on the

inking rollers as the printing press comes to a stop.

13. The method of preventing the solidification of printing ink on the inking rollers of a printing press which comprises the application of a finely divided liquid spray of slowly evaporating liquid miscible with the printing ink base to the printing ink upon the inking rollers for a definite predetermined period of time as the printing press comes to a stop from an operating speed.

14. The method of preventing the solidification of printing ink on the inking rollers of a printing press consisting of the application of a finely divided liquid spray of slowly evaporating liquid miscible with the printing ink base to the printing ink upon the inking rollers for a definite predetermined minimum period of time upon the operation of the printing press at a predetermined relatively low speed.

15. The method of treating water base printing ink on the inking rollers of a printing press comprising the application of a finely divided spray of a hygroscopic liquid to the printing ink upon the inking roller as the printing press comes to a stop from an operating speed.

16. The method of treating water base printing ink on the inking rollers of a printing press comprising the application of a finely divided spray of a hygroscopic liquid to the printing ink upon the inking rollers for a definite predetermined minimum period of time upon the operation of the printing press at a predetermined relatively low speed.

17. The method of preventing the solidification upon the inking rollers of a printing press of printing inks whose essential ingredients are carbon and water which comprises the application of a finely divided spray of glycerine to the printing ink upon the inking rollers when the printing press is brought to a stop from an operating speed.

18. The method of preventing the solidification upon the inking rollers of a printing press of printing inks whose essential ingredients are carbon and water which comprises the application of a finely divided spray of glycerine to the printing ink upon the inking rollers for a predetermined minimum period of time as the printing press is brought to a stop from an operating speed.

19. The method of preventing the solidification upon the inking rollers of a printing press of printing inks whose essential ingredients are carbon and water which comprises the application of a finely divided spray of glycerine to the printing ink upon the inking rollers for a predetermined minimum period of time upon the operation of the printing press at an inching speed.

20. The method of treating water base printing ink on the inking rollers of a printing press comprising the application of a finely divided water spray to the printing ink upon the inking rollers for a definite predetermined minimum period of time upon the operation of the printing press at a predetermined relatively low speed.

21. The method of preventing the solidification upon the inking rollers of a printing press of printing inks whose essential ingredients are carbon and water which comprises the application of a finely divided water spray to the printing ink upon the inking rollers when the printing press is brought to a stop from an operating speed.

22. The method of preventing the solidification

upon the inking rollers of a printing press of printing inks whose essential ingredients are carbon and water which comprises the application of a finely divided water spray to the printing ink upon the inking rollers for a predetermined minimum period of time as the printing press is brought to a stop from an operating speed.

23. The method of preventing the solidification upon the inking rollers of a printing press

of printing inks whose essential ingredients are carbon and water which comprises the application of a finely divided water spray to the printing ink upon the inking rollers for a predetermined minimum period of time upon the operation of the printing press at an inching speed.
